TENS TRANSMITTING DEVICE FOR ADDING MACHINES

Tord Olof Rickard Dahlberg, Nockeby, Sweden

Application May 18, 1935, Serial No. 22,148
In Sweden September 13, 1934

4 Claims. (Cl. 235—138)

The present invention relates to a tens transmitting device for adding machines having a disconnectable totalizer wheel shaft and having a counting rack displaceable on a setting bar, which is displaceable nine pitches, the said counting rack being adapted during the tens transmitting to be moved one pitch after the setting bar has returned to the zero position and while the totalizer is still in engagement. The said tens transmitting device, which in the first place is intended to be used in cash registers, is made for the purpose of obtaining positive and safe tens transmitting. In constructing the device it has, therefore, been necessary to try to obtain a considerable reduction of the number of members constituting the tens transmitting means used heretofore at the same time as it has been necessary to pay attention thereto that already each separate part has worked reliably and safely and that a durable shape has been given to the same. The intended purpose has also been reached by the device according to the invention and the device is characterized substantially thereby that a pawl, which is pivotable on a stationary shaft, is adapted during tens transmitting to be brought into such position (operative position) by the counting wheel that it blocks a tens transmitting element moving parallel to the setting bar and forces the latter to change its position and to displace the said counting rack at the same time.

An embodiment of the invention is illustrated diagrammatically in the accompanying drawings, the parts constituting the device being shown in Figures 1 and 2 in two different positions.

In the drawings, numeral 1 indicates the toothed wheel of the totalizer wheel 2, the shaft 3 of the former being displaceable towards and away from the counting rack 5, which is displaceable on the setting bar 4. The counting rack, which is guided by two pins 6 extending into longitudinal slots 7 provided in the rack 5 tends to be held in the position shown in Figure 1 by a spring 8. The setting bar 4 may be displaced nine pitches the slots 7 of the counting rack only admitting of a displacing movement of the last mentioned rack corresponding to one pitch. In the type of adding machines in question, as shown for instance in U. S. Patent No. 1,185,696, and U. S. Patent 2,091,758, this latter displacement, which occurs during the tens transmitting takes place after the setting bar has returned to the zero position, but while the totalizer is still in engagement, thus, when the parts assume the positions shown in Figure 1. In order that this tens transmitting shall take place positively

there is, according to the invention, provided a pawl 10 pivotally disposed on a stationary shaft 9, the said pawl consisting of a two-armed lever in the embodiment shown. During the tens transmitting the said pawl is adapted to be brought into such operative position by means of a shoulder, pin or the like 11 of the totalizer 2 that it comes in the path of a tens transmitting element 12 movable in the return direction of the setting bar. The element 12 consists of a two-armed lever, which is pivotally connected parallel to a member 13 moving with the setting bar 4, the said member receiving its motion from a cam disk or the like. In its operative position the pawl 10 is adapted to force the tens transmitting element 12 to change its position whereby said counting rack is displaced.

To retain the pawl 10 in operative and inoperative position respectively there is provided a draw spring 14, one end of which is united with one end of the pawl 10 and the other end of which is fixed on a pin 15 so located relative to the pivot 9 of the pawl, that the lever 10, when it is between two stationary shoulders 16, 17, which limit the pivoting movement of the pawl, will assume a position of unstable equilibrium. To return the tens carrier element 12 to the initial position there is a pressure spring 18.

When a ten is to be transmitted the pin 11 of the totalizer wheel 2 of the next lower denomination actuates one end of the pawl 10 and moves the pawl in the direction of the arrow indicated in Figure 1, the pawl, when the position of unstable equilibrium has been passed, being automatically forced by the spring 14 over to the active position shown in Figure 2. The turning of the totalizer wheel takes place during the downwardly directed movement performed by the setting rack with connected counting rack in order to reach its resting or zero position. When the said position has been reached, the member 13 moves towards its lower end position, the pawl 10 blocking one end of the tens transmitting member 12, and its other end, which is being pivoted downwards, actuating the counting rack 5 representing the next higher value and displacing the same one pitch, a corresponding turning being imparted to the counting wheel, which is in engagement with the rack in question. After, in the above described manner, all tens have been released or transmitted in their proper turns the totalizer wheel shaft 3 together with totalizer wheels blocked thereon is displaced away from the setting bar, whereby also the

counting rack 5 is released and by means of a spring 8 is returned to its initial position.

A pivotable link 20, which is provided with a projecting pin 19 or the like, upon each displacement of the totalizer wheel shaft 3 away from the setting bar 4 forces the pawl 10 back to its inoperative initial position. The link 20 is actuated against a spring 21 by means of some suitable driving device, for example lever arm 22 engaged with the totalizer wheel shaft 3 so as to transmit to link 20 a pivoting movement in the direction indicated by an arrow in Figure 2.

The operation is as follows. When the machine is started the counting wheels are out of engagement with the racks 5, the latter assuming the relative positions with respect to the bars 4 shown in Figure 1. By key actuation the bars and racks of the machine are then caused to assume positions of various heights corresponding to various numerical values, but the positions of the bars 4 and racks 5 with respect to each other are, however, unchanged. When setting has taken place the counting wheels enter into engagement with the bars and racks and when the racks are moved in downward direction the wheels are rotated by amounts corresponding to the setting of the bars. If, however, the counting wheels, when entering into engagement with the racks, assume positions corresponding to the figure 999 and only the unit figure "one" has been entered on the machine, the pin 11 of the unit wheel, when the racks move downwards, will actuate, when the wheel passes from 9 to 0, the pawl 10 of the tens' wheel and shift said pawl to the position shown in Figure 2. When the bars 35 have reached their home or normal position, all of the members 13 begin to move downwards beginning with the tens' member and continuing with the hundreds' member etc. in their proper turns. During this movement the member 12, which is carried by the tens' member 13, hits the corresponding pawl 10, by which the corresponding counting rack 5 is displaced one more pitch. During this operation the tens' counting wheel is shifted from 9 to 0, whereupon the pin 45 11 of the said wheel shifts the pawl 11 corresponding to the hundreds' wheel, and when the corresponding member 13 reaches its lower position the hundreds' wheel, via the counting rack, is shifted from 9 to 0, and in this manner the 50 transmission is continued until all of the counting wheels have been shifted. After that the counting wheels move out of engagement with the racks and the members 13 move to their upper positions whereupon the bars 4 and racks 5 reassume the relative positions shown in Figure 1.

Several embodiments may of course be devised within the scope of the invention and the various members or elements may be shaped and also be combined in manifold different ways.

Having now described my invention, what I claim as new and desire to secure by Letters Patent is:

1. An adding machine comprising for each denomination a setting bar, a counting rack carried on and displaceable one pitch with respect to said setting bar, a reciprocating totalizer wheel adapted to be alternately engaged by and disconnected from said counting rack, a cam controlled member movable in a direction parallel to the counting rack, each member of the successive denominations being actuated in its proper turn when the setting bar is in its home position and the totalizer wheel is still in engagement with the counting rack, a displaceable abutment element disposed on said cam controlled member for engagement with the counting rack, means to normally keep said element in an inoperative position, a stationary support, a transfer initiating pawl pivoted on said support, means on the totalizer wheel of the next lower denomination to bring said pawl into a predetermined position in the path of said abutment element on said cam controlled member, when said totalizer wheel of the next lower denomination passes from nine to zero, and means to retain said pawl in said position, whereby said abutment element encounters said pawl during movement of said cam controlled member and is displaced so as to transmit one pitch of said movement to the counting rack and totalizer wheel. 35

2. The combination set forth in claim 1, in which said abutment element also comprises a two-armed pivotable lever, one arm being encounterable by the pawl when the latter is in operative position, the other arm engaging with the 40 counting rack.

3. The combination set forth in claim 1, in which said pawl comprises a two-armed lever, in combination with stationary shoulders limiting the pivotal movements of the lever, and said 45 means to retain the pawl in operative position include a dead center spring actuator for urging the lever into one or the other of its extreme positions.

4. The combination set forth in claim 1, including further means arranged to be actuated by the reciprocating movement of said totalizer wheel and restoring said pawl to its inoperative position when said totalizer wheel is disconnected from said counting rack. 50
